ENVELOPE

Francis E. Carroll, Worcester, Mass., assignor to
United States Envelope Company, Springfield,
Mass., a corporation of Maine

Application September 4, 1943, Serial No. 501,258

6 Claims. (Cl. 43—146)

The present invention relates to envelopes used as containers for those finely powdered materials, such as disinfectants, insecticides, and the like, which need, for best results, to be thoroughly and uniformly distributed, as by dusting or blowing the same onto the areas to be treated.

My invention contemplates an envelope or bag for this purpose, so constructed as to serve as a bellows, for the forcible expulsion of its powdered contents through suitable slits or openings at one end thereof—the envelope material itself providing integral flap extensions or tabs readily seizable on opposite sides of the envelope body, to enable a bellows action to be imparted. Other and further objects and advantages of the invention will more fully appear from the following detailed description thereof, taken in connection with the accompanying drawing, in which—

Fig. 1 is a plan view of the blank from which the envelope of my invention is constructed.

Fig. 2 shows the initial folding of said blank, in the act of forming the envelope pocket.

Fig. 3 shows the second part of this initial folding operation.

Fig. 4 is a plan view of the completed envelope, with one end left open for the introduction of the contents thereof.

Fig. 5 is a view similar to Fig. 4 of the reverse side of the envelope, and showing the flap at its filling end in closed position, and

Fig. 6 is a perspective view, illustrating the bellows action of said envelope, in the dusting discharge of its contents.

Like reference characters refer to like parts in the different figures.

The envelope of my invention is preferably made from strong durable paper stock, such as manila, kraft, or the like, which is cut to provide blanks of substantially the shape and configuration shown by Fig. 1. Each such blank, as shown in Fig. 1, comprises a generally rectangular body portion 1, as outlined laterally by the broken lines 2, 3, and at one end by the broken line 4 and at the other end by an edge 5—the latter preferably being cut away or recessed, as shown at 6, for a purpose to be hereinafter described. Flanking the body portion 1 along its two sides are the integral side flaps 7 and 8; one of these side flaps (the flap 7) includes a substantially rectangular portion 9 which is nearly coextensive in area with the body portion 1, and in addition includes, beyond the latter's end edge 5, an elongated extension 10. Said extension 10, just below its line of juncture 11 with flap portion 9, is formed with a row of apertures 12, 12 through

which, in the completed envelope, the latter's powdered contents are adapted to be forcibly expelled or blown by a bellows action, as herein-after described.

5 The other side flap 8 for most of its length is considerably narrower than the body portion 1 and the side flap 7. Only near one end (the end adjacent to edge 5 of the body portion 1) does the flap 8 need to be substantially coextensive in 10 width with said body portion—this increased width being for the purpose of giving said flap 8 beyond said edge 5 an extension 13, much shorter than the extension 10 of the other side flap 7, and serving, as hereinafter described, as a releasable closure for the discharge openings 12, 12. The flap 8 about midway of its length is formed with a laterally extending tab 14. Also projecting from the body portion 1 is an end flap 15 of substantially conventional form, to serve as 15 a final sealing closure for the pocket of the completed envelope after the latter has received its contents.

With glue or other adhesive applied, as shown 20 by the stippling, to the side flap 8, the latter's extension 13, and to the extension 10 of the side flap 7, the first operation in the manufacture of 25 my improved envelope is to fold over the side flap 7 along the line 3 onto the body portion 1, as shown in Fig. 2; the second operation is to fold 30 over the side flap 8 along line 2 (see Fig. 3), and then adhesively uniting the flaps 7 and 8 over the entire area of their overlap, except for the unglued tab portion 14 of said flap 8. Said folding down of flap 8 also effects an adhesive union of 35 limited area between the flap extensions 10 and 13, this resulting from the spot or area 16 of moist glue on extension 13 which is contacted with the unglued side of the extension 10 in the overlapped relation of these parts shown by Fig. 3, with the 40 edge of flap 13 left free as a pull tab 18.

The next operation in the manufacture of the envelope of my invention is a transverse folding 45 operation, substantially along the line 11, to close one end of the flat tube (Fig. 3) that has been formed by the overlapping, as above described, of side flaps 7 and 8. This transverse folding on line 50 11 thus involves the two overlapped flap extensions 10 and 13, and occurs in a direction away from the envelope's side or wall, Fig. 3, that is 55 formed by the overlapped flaps 7 and 8. That is to say, the folding on line 11 is in such a direction as to carry the flap extensions 10 and 13 down against the unseamed envelope side or wall formed by the rectangular body portion 1, thus disposing said extensions 10 and 13 (see Figs. 4

and 5) against the opposite side of the envelope from the side which is constituted by the overlapping flaps 7 and 8. Such folding down adheres the entire glued area of extension 10 to the outside surface of body portion 1, and it will be noted in this connection that this gluing of extension 13 terminates well short of the latter's free end, leaving an unglued tab portion 17 that normally lies flat against an approximately central portion of the unseamed envelope wall, in substantially opposite relation to the ungummed tab portion 14, normally lying flat against the other or seamed wall of the envelope.

Such folding over and gluing down of the extension 10 obtains the closure of the envelope pocket at its lower end, notwithstanding the presence at said end of the openings 12, 12 communicating with the pocket interior; the reason for this being the fact that these openings are covered and rendered ineffective by the flap extensions 13, the latter being folded over with extension 10 and being adhesively connected by the limited glue area 16 with the exposed or outside face of extension 10. By this folding and sticking down of the flap extensions 10 and 13, the envelope of my invention is completed—it being understood that the other end of the envelope is left open for the introduction of the powdered material which subsequently, in the use of the envelope, is to be discharged through the openings 12, 12. After the desired amount of such powdered material has been introduced into the envelope pocket through its open end the flap 15 is folded over and permanently adhered by its glue to the seamed envelope wall—the line 15 of such fold, defined, if desired, by transverse scoring of the envelope walls, being preferably positioned to include the upper edges of said walls, thereby to make the closed package (Fig. 5) leak-proof at its upper corners.

It will be noted that the gummed area 16 of extension 13 does not extend to the latter's edge, said edge being left free and ungummed, to constitute a pull tab 18 by which the flap or extension 13 may be seized and pulled away, to break its limited adhesion with the underlying outside surface of the permanently-glued-down flap or extension 10. Such pulling away of flap or extension 13 exposes and renders operative the openings 12, 12 through which the powdered contents of the envelope are to be discharged. My invention thus provides an envelope which, after the flap 13 has been lifted to expose the discharge openings 12, 12, can be seized, in the manner shown in Fig. 6, by the two tabs or fins 14 and 17 of its sides or walls, to give by repeated flexures a bellows action to said walls toward and from each other, thus to forcibly blow the powdered contents through the discharge openings 12, 12 for a thorough and uniform dusting of the areas or surfaces toward which the openings are pointed.

I claim:

1. An envelope for containing and dispensing powdered material, and made from a single blank having side and end flaps adapted to be folded and glued to provide the two side walls and the transverse top and bottom closures of the envelope pocket, said bottom closure having perforations normally covered and rendered ineffective by a stuck-down flap extension of said blank, the material of said blank providing near the center of each side wall an integral unstuck fin or tab, for seizure by the user to impart flexure and a bellows action to said side walls, for the

forcible discharge of the envelope's contents through said perforations, upon exposure of the latter by the lifting or release of said flap extension.

5 2. An envelope for containing and dispensing powdered material, made from a blank having a substantially rectangular body portion forming one wall of the envelope, said blank having a pair of opposite side flaps adapted to be folded over into overlapping adhesive engagement to form the other wall of said envelope, a top flap adapted to be folded transversely and adhesively secured to said folded side flaps, a bottom flap adapted to be folded transversely and adhesively secured to the first-named wall to provide the envelope's bottom closure, the bottom closure having a stuck-down tab at one end of one of said side flaps, said bottom closure having perforations normally covered and rendered ineffective by said stuck-down tab which has a common line of fold with said bottom flap, a free unstuck tab midway on the side flap which has said stuck-down tab, and a second free unstuck tab provided by said bottom flap on the opposite wall of the envelope, said two unstuck tabs serving for seizure by the user to impart flexure and a bellows action to said walls of the envelope, for the forcible discharge of the envelope's contents through said perforations, upon exposure of same by lifting or release of said stuck-down tab.

3. As a new article of manufacture, a bellows-action envelope made from a one-piece blank having a substantially rectangular body portion forming one wall of the envelope, and having a pair of opposite side flaps adapted to be folded over into overlapping adhesive engagement to form the other wall of the envelope, said blank having a pair of transversely foldable end flaps forming the top and bottom closures of the envelope there being a discharge near one of said folds, one of said end flaps extending from a side flap and adhesively connected beyond its fold with the first-named envelope wall, and having at its end, substantially centrally of said wall, an unstuck tab, and the other side flap providing, on the opposite envelope wall, a second unstuck tab, said two unstuck tabs serving for seizure by the user to impart flexure and a bellows action to the walls of the envelope, for forcible discharge of its contents.

4. As a new article of manufacture, a bellows-action envelope made from a one-piece blank having a substantially rectangular body portion forming one wall of the envelope, and having a pair of opposite folded-over side flaps adapted to be joined adhesively at their overlapping edges to form the seam of the other wall of the envelope, said blank having a pair of opposite transversely foldable end flaps forming the top and bottom closures of the envelope, one of said end flaps extending from a side flap and being secured adhesively beyond its fold to the first-named envelope wall, with its extremity left free and unstuck, to form a tab substantially centrally of said wall, and a second free unstuck tab provided by one of said side flaps on the opposite envelope wall substantially centrally of said seam, said two tabs serving for seizure by the user to impart flexure and a bellows action of said walls of the envelope for the forcible discharge of its contents through an opening in the envelope material.

5. An envelope for containing and dispensing powdered material, said envelope being a one-piece structure having a body portion to pro-

vide one wall, side portions each having a fold connection with the body portion and secured to each other in overlapped relation to provide the other envelope wall, a closure having a fold connection with one wall at one end thereof and adapted to be adhesively secured to the other wall, a second closure comprising two parts having fold connections with the side portions and being adhesively secured to each other and to the body portion, one of said parts having openings therein and a tab, the other part being adapted to cover said openings, and a tab extending from one of the side portions whereby when the openings are uncovered the tabs may be manipulated to produce flexure of said walls for the forcible discharge of the envelope's contents through said openings.

6. As a new article of manufacture, an envelope for containing and dispensing powdered material, said envelope being a one-piece struc-

ture having a body portion to provide one envelope wall, side portions each having a fold connection with the body portion and adhesively secured to each other in overlapped relation to provide the other envelope wall, an end closure having a fold connection with one of said walls and adapted to be adhesively secured to the other wall, and an opposite end closure having a fold connection with one of said side portions and adhesively secured to the first mentioned wall, one of said side portions and said second-mentioned end closure providing integral extensions, free of adhesive connection to the respective associated walls, said extensions providing tabs on the opposite walls for seizure by the user to produce flexure and a bellows action of said walls for the forcible discharge of the envelopes' contents when an opening is provided in the envelope material.

20
